X-RAY PROCESSING TANK

John W. Carr, Pacific Palisades, Calif.

Application December 16, 1957, Serial No. 48,905

Term of patent 14 years

(Cl. D61—1)

FIG. 1.

FIG. 2.

Fig. 1 is a perspective view of the front and right side of an X-ray processing tank showing my new design; and

Fig. 2 is a side elevational view of the left side thereof on a reduced scale.

The back, not shown, is conventional. A portion of Fig. 1 is diagonally lined to indicate translucency.

I claim:

The ornamental design for an X-ray processing tank, as shown and described.
